ATTORNEY.

BY

Patented Mar. 15, 1927.

UNITED STATES PATENT OFFICE.

IRWIN E. RICE, OF DENVER, COLORADO.

BRUSH.

Application filed July 24, 1925. Serial No. 45,760.

An object of this invention is to provide an improved construction for a brush particularly adapted for cleaning containers such as bottles and jugs on the inside.

5 A further object of this invention is to provide improved means for expanding and contracting a brush laterally of its median line.

10 A further object of this invention is to provide improved means for mounting brush elements on an expandable and contractable frame.

15 My invention consists in the construction, arrangement and combination of elements hereinafter set forth, pointed out in the claims and illustrated by the accompanying drawing, in which—

20 Figure 1 is a side view of my improved brush, shown closed or contracted in solid lines and expanded in dotted lines. Figure 1. 2 is a view at right angles to Figure 1. Figure 3 is a cross-section on the indicated line 3—3 of Figure 1. Figure 4 is a cross-section on the indicated line 4—4 of Figure 1.

25 In the construction of the device as shown the numeral 10 designates generally a re-curved handle, preferably formed of a metal bar having parallel stem portions 10', 10" formed on the end portion of the bar and an elongated wider loop portion 10''' at the center of the bar, the sides of the loop portion being substantially parallel and the outer end thereof being arcuate. Frame 30 members are provided on opposite sides of the median line of the handle and each frame member is formed of two channel bars of unequal length, the shorter bars being designated by the numerals 11 and 13 and the longer bars being designated by the numerals 12 and 14. The channel bars of the frame members have their channels opening outwardly relative to the median line of the brush and one end each of the shorter bars 11, 13 is pivoted to the extremity of one of the arms of the stem portion, 10', 10'', while the outer end portion of each shorter bar is pivoted to the inner end portion of a longer bar 12 or 14. Collars 35 15, 16 are mounted on and fixed in spaced relation to the stem portion of the handle and serve to hold the arms 10', 10'' in fixed spaced relation. A push rod 17 is slidingly mounted in the handle and is confined by the collars 15, 16 which, together with the arms 10', 10'' form a slide bearing there-

for, and said push rod extends forwardly from the collar 16, when the device is in contracted position, substantially to the outer ends of the channel bars 12, 14. The 60 push rod is formed with an eye or loop 18 on its inner end between the sides of the loop portion 10''' of the handle and the diameter of said eye is in the plane of said sides. The forward end portion of the push 65 rod 17 is flattened in the planes of the side margins of the channel bars 11, 12, 13 and 14 and connecting rods 19, 20 and 21, 22 are employed pivotally to connect said push rod to the channel bars. The rods 19 and 20 are 70 pivoted at their rear ends to the joints between the channel bars while the rods 21 and 22 are pivoted at their rear ends to the central portions of the bars 12 and 14. The forward end portions of the rods 19 and 20 75 are coincidentally pivoted to the push rod 17 by a pin 23 intersecting the flattened faces of said push rod, while the forward end portions of the rods 21 and 22 are coincidentally pivoted to the forward end portion 80 of the push rod by a pin 24 intersecting the flattened faces of said push rod. Thus provision is made for maintaining the parallel positions of the bars 12 and 14 irrespective of the spacing of said bars relative to the 85 push rod 17. Brush members are mounted on the frame members and preferably are constructed of twisted wire cores 25, 26 and bristles 27 mounted between the wires constituting each core. Rear end portions of 90 the cores 25, 26 are extended through and clenched on the inner faces of the rear portions of the channel bars 11 and 13 while the forward end portions of said cores extend through and are clenched on the inner surfaces of the outer end portions 95 of the channel bars 12 and 14. The body portions of the cores 25, 26 draw into the channels of the bars 11, 12, 13 and 14, particularly when the frame members are in expanded positions. Any suitable means may 100 be employed for securing the brush elements to the frame members. Primarily the brush elements project radially as arcuate bodies outside of the frame members, but in use they tend to become disarranged and extend radially substantially around the cores 25, 26 except where prevented by the frame members.

105 In practical use the device may be employed generally for brushing purposes in any condition of expansion or contraction.

The device may also be contracted fully, by pushing the rod 17 outwardly relative to the handle through manual force applied to the eye 18 and, when so contracted it 5 may be introduced through a restricted neck of a bottle, jug or other container or through either open end of a lamp chimney or globe. After being introduced to the device to be cleaned, the brush may be expanded to any 10 desired degree, by pulling the push rod 17 through manual force applied to the eye 18, thereby causing the bristles 27 to engage the inner wall of the object to be cleaned. Thereafter the tool may be rotated, oscillated or reciprocated in the object to be 15 cleaned to the end of cleansing or polishing the inner surface of said object. It is to be understood that the tool may be employed dry either with or without cleaning or polishing powder, or it may be employed with any desired cleaning or polishing liquid or solution.

I claim as my invention—

1. A brush comprising a skeleton handle,

spaced collars on said handle whereby a 25 slide bearing is formed, a push rod slidingly mounted in said handle and adapted for manual adjustment relative thereto, channel bars pivoted to said handle, other channel bars pivoted to the first channel bars, rods 30 pivotally connecting said push rod to said channel bars and brush elements mounted on and projecting outwardly from said channel bars.

2. A brush comprising a skeleton handle 35 having a stem and a looped end portion, spaced collars on said stem portion, a push rod slidingly mounted in said handle and extending through said collars, jointed frame members pivoted to said handle and 40 extending on opposite sides of said push rods, toggle connections between said push rod and frame members and brush elements carried by said frame members.

Signed at Denver, in the county of Denver 45 and State of Colorado, this 27th day of June, 1925.

IRWIN E. RICE.
